(57) **CLAIM**

The ornamental design for a scooter, as shown and described.

DESCRIPTION

FIG. 1 is a perspective view of a scooter showing my new design;
FIG. 2 is another perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof;
FIG. 8 is a bottom plan view thereof;
FIG. 9 is an enlarged view of area “9” in FIG. 1;
FIG. 10 is an enlarged view of area “10” in FIG. 1;
FIG. 11 is an enlarged view of area “11” in FIG. 1;
FIG. 12 is an enlarged view of area “12” in FIG. 2;
FIG. 13 is an enlarged view of area “13” in FIG. 2; and,
FIG. 14 is an enlarged view of area “14” in FIG. 2.
The evenly spaced broken lines denote portions of the article that form no part of the claimed design. The dash-dot broken lines shown in FIGS. 1, 2, and 9-14 are for the purpose of indicating the enlarged partial views and form no part of the claimed design.

1 Claim, 14 Drawing Sheets
